GLASS CUTTER

Richard C. Barrett, Bristol, Conn., assignor of
one-half to Robert W. Barrett, Cambridge,
Mass.

Application December 14, 1939, Serial No. 309,122

3 Claims. (Cl. 49—52)

This invention relates to improvements in glass cutters and the principal object of the invention is to provide a glass cutter with a hood normally overlying and protecting the cutting member from injury, but removable from normal position to permit unhampered use of the cutter particularly when the cutter is directed by a suitable straight edge or other guide.

Another object of the invention is to provide a glass cutter comprising a handle and a narrow body terminating in a bifurcated acute angled end having a rotary cutter disk mounted therein with a guard normally positioned to protect said cutter, but removable therefrom to a position in which it will permit unhampered use of the cutter and comprising lubricating means adapted to engage the cutter when the guard is in normal cutter-protecting position.

A further object of the invention is to provide a glass cutter of the class described having a rotatable cutting disk with a guard member formed of resilient sheet metal having a hood to overlie and enclose the glass cutter and provided with integral parallel arms frictionally engaging the sides of the cutter body and pivotally connected thereto and adapted to be swung from normal position to a position in which engagement with a straight edge or other guiding means will be avoided.

These and other objects and features of the invention will more fully appear from the following description and the accompanying drawing and will be particularly pointed out in the claims.

A preferred embodiment of the invention is illustrated in the accompanying drawing, in which,

Fig. 1 is a side elevation of a glass cutter provided with a protecting guard for the cutter showing also the position of the guard member when swung from normal position to permit unobstructed use of the cutter;

Fig. 2 is a top plan view of the cutter and guard illustrated in Fig. 1;

Fig. 3 is an enlarged vertical sectional view of the glass cutter and a portion of the handle particularly illustrating the position of the guard member in normal position with an oil saturated member engaging the cutter, and also showing in dotted lines the position of the cutter when removed from normal position to permit use of the cutter; and,

Fig. 4 is a view of the glass cutter and guard illustrated in Figs. 1, 2, and 3, showing the guard in retracted position and illustrating the manner

in which the cutter is directed by a straight edge or other guide in cutting a sheet of glass which is illustrated in section.

The glass cutter illustrated in the accompanying drawing comprises a metallic handle member 1 and an integral relatively narrow head 2 having parallel sides, the handle member having a concave depression 3 in proximity to said head and converging outwardly therefrom and preferably terminating in a spheroidal end 4 adapted to be used as a hammer to break edge portions of the glass beyond the line which is scored by the cutter. The head 2 terminates in a bifurcated acute angled end. A cutter disk 5 having a sharp periphery is rotatably mounted upon a suitable shaft 6 in the bifurcated end of the body with its periphery projecting therebeyond in such manner as to engage and to cut the glass. The head is provided with usual rectangular slots 7, 8, and 9 of different widths adapted to engage portions of glass of different thickness which extend beyond the cutting line and by angular movement of the handle to break away such projecting portions.

The cutter thus described may be and is of a usual form. The present invention comprises means normally protecting the cutter disk from injury if the cutter should be inadvertently dropped upon a hard surface and also to protect

the cutter when carried in the pocket. The preferred form of guard illustrated comprises a thin resilient sheet metal hood 10, preferably of semi-cylindrical form, adapted to overlie and partially to embrace the cutter disk with integral parallel resilient arms 11 and 12 engaging the flat parallel sides of the body and pivotally connected near their ends to the body at such distance from the end of the body as will permit the guard to be swung from normal position to a position in

which it will not engage the straight edge or other guide for directing the cutter along the pane or plate of glass to be cut, as illustrated in dotted lines in Figs. 1 and 4.

Any suitable means may be provided for pivotally connecting the guard to the cutter body. In the preferred construction illustrated the body is provided with oppositely disposed sockets 13 and the resilient arms 11 and 12 of the guard are punched inwardly to provide nibs adapted to detachably engage the sockets 13 and thereby provide a pivotal connection. The resilience of the arms is such as to hold the nibs in engagement with the sockets and also to cause such frictional engagement between the arms and the sides of the body as to hold the guard in retracted posi-

tion illustrated in Figs. 1 and 3 when the cutter is to be used.

By reason of the detachable connection between the arms of the guard member and the side of the body of the glass cutter, the guard may be easily removed and replaced. Furthermore, the guard member can be readily applied to a usual form of glass cutter by merely punching or drilling indentations in proper locations in the side of the glass cutter, or by drilling through the glass cutter to provide sockets to receive the inwardly extending nibs of said arms.

An arcuate end portion 14 is severed along the lines 15 and 16 from the hood portion 10 of the guard so that the resilient arcuate end portion 14 will, when the guard is swung from dotted line position illustrated to normal position shown in full lines, snap over the cutter disk and retain the guard in cutter-protecting position.

Suitable oil-saturated means, such as a pad 17 is cemented or otherwise secured to the inner face of the guard and preferably also to the arcuate end portion and is adapted to engage the cutter disk when the guard is in disk-protecting position, thereby lubricating the cutter disk and the bearings of its shaft. Such lubrication of the cutter disk will protect it from rust and consequent pitting of the cutting edge thereof. The pad also provides a cushion which will prevent injury to the edge of the disk when the hood is in cutter-protecting position particularly if the glass cutter is dropped in such manner that the cutter disk would otherwise engage a hard object.

It is usually desirable in cutting a plate or pane of glass to employ a straight edge or other guide for accurately directing the cutter along the desired line and it will be noted by reference to Fig. 4 that the side of the cutter is being directed by a straight edge or guide 18 along the pane or plate of glass 19 and that at such time the guard is swung upwardly into such position that it cannot engage the guide or otherwise obstruct the use of the cutting tool. Desirably the arms of the guard are pivotally connected to the head approximately midway of its length so that when the guard is in raised position, as illustrated in Figs. 1, 2, and 4, the end of the guard lies in proximity to the rear end of the cutter, and also in a position in which it may be engaged by the finger of the operator when the finger is positioned in the concave depression 3 which is provided to enable the operator to exert pressure upon the cutter.

It will be understood that the particular embodiment of the invention disclosed herein is of an illustrative character, and that various changes in form, construction and arrangement of parts may be made within the spirit and scope of the following claims.

Having thus described the invention, what is claimed as new, and desired to be secured by Letters Patent, is:

1. A glass cutter comprising a handle and a narrow head having parallel sides and terminating in a bifurcated acute-angled end, a cutter disk

65 rotatably mounted in said bifurcated end with its periphery projecting therebeyond, a guard member for protecting said cutter comprising a semi-cylindrical hood of thin resilient sheet metal normally fitting over said cutter disk and the end of said head and having integral sides partially severed from the cylindrical portion of the hood to provide a flexible arcuate section adapted to snap over the disk and resilient parallel arms integral with and extending from the sides of said hood frictionally engaging the flat sides of said head, and detachable means pivotally connecting said arms to said head at such distance from the end of said head as will enable a flat side of the head to be directed along a suitable guide without engagement of the guard with the guide.

2. A glass cutter comprising a handle and a narrow head having parallel sides and terminating in a bifurcated acute-angled end, a cutter disk rotatably mounted in said bifurcated end with its periphery projecting therebeyond, a guard member for protecting said cutter comprising a semi-cylindrical hood of thin resilient sheet metal normally fitting over said cutter disk and the end of said head and having integral sides partially severed from the cylindrical portion of the hood to provide a flexible arcuate section adapted to snap over the disk and resilient parallel arms integral with and extending from the sides of said hood frictionally engaging the flat sides of said head, and complementary nibs in said arms and sockets in said head detachably and pivotally connecting said arms to said head at such distance from the end of said head as will enable a flat side of the head to be directed along a suitable guide without engagement of the guard with the guide.

3. A glass cutter comprising a handle and a narrow head having parallel sides and terminating in a bifurcated acute-angled end, a cutter disk rotatably mounted in said bifurcated end with its periphery projecting therebeyond, a guard member for protecting said cutter comprising a semi-cylindrical hood of thin resilient sheet metal normally fitting over said cutter disk and the end of said head and having integral sides partially severed from the cylindrical portion of the hood to provide a flexible arcuate section adapted to snap over the disk and resilient parallel arms integral with and extending from the sides of said hood frictionally engaging the flat sides of said head, detachable means pivotally connecting said arms to said head at such distance from the end of said head as will enable a flat side of the head to be directed along a suitable guide without engagement of the guard with the guide.

40 4. A glass cutter comprising a handle and a narrow head having parallel sides and terminating in a bifurcated acute-angled end, a cutter disk rotatably mounted in said bifurcated end with its periphery projecting therebeyond, a guard member for protecting said cutter comprising a semi-cylindrical hood of thin resilient sheet metal normally fitting over said cutter disk and the end of said head and having integral sides partially severed from the cylindrical portion of the hood to provide a flexible arcuate section adapted to snap over the disk and resilient parallel arms integral with and extending from the sides of said hood frictionally engaging the flat sides of said head, detachable means pivotally connecting said arms to said head at such distance from the end of said head as will enable a flat side of the head to be directed along a suitable guide without engagement of the guard with the guide.

45 5. A glass cutter comprising a handle and a narrow head having parallel sides and terminating in a bifurcated acute-angled end, a cutter disk rotatably mounted in said bifurcated end with its periphery projecting therebeyond, a guard member for protecting said cutter comprising a semi-cylindrical hood of thin resilient sheet metal normally fitting over said cutter disk and the end of said head and having integral sides partially severed from the cylindrical portion of the hood to provide a flexible arcuate section adapted to snap over the disk and resilient parallel arms integral with and extending from the sides of said hood frictionally engaging the flat sides of said head, detachable means pivotally connecting said arms to said head at such distance from the end of said head as will enable a flat side of the head to be directed along a suitable guide without engagement of the guard with the guide.

50 6. A glass cutter comprising a handle and a narrow head having parallel sides and terminating in a bifurcated acute-angled end, a cutter disk rotatably mounted in said bifurcated end with its periphery projecting therebeyond, a guard member for protecting said cutter comprising a semi-cylindrical hood of thin resilient sheet metal normally fitting over said cutter disk and the end of said head and having integral sides partially severed from the cylindrical portion of the hood to provide a flexible arcuate section adapted to snap over the disk and resilient parallel arms integral with and extending from the sides of said hood frictionally engaging the flat sides of said head, detachable means pivotally connecting said arms to said head at such distance from the end of said head as will enable a flat side of the head to be directed along a suitable guide without engagement of the guard with the guide.

55 7. A glass cutter comprising a handle and a narrow head having parallel sides and terminating in a bifurcated acute-angled end, a cutter disk rotatably mounted in said bifurcated end with its periphery projecting therebeyond, a guard member for protecting said cutter comprising a semi-cylindrical hood of thin resilient sheet metal normally fitting over said cutter disk and the end of said head and having integral sides partially severed from the cylindrical portion of the hood to provide a flexible arcuate section adapted to snap over the disk and resilient parallel arms integral with and extending from the sides of said hood frictionally engaging the flat sides of said head, detachable means pivotally connecting said arms to said head at such distance from the end of said head as will enable a flat side of the head to be directed along a suitable guide without engagement of the guard with the guide, and an oil-saturated lubricating pad concentric with and fitted within the cylindrical portion of said hood normally embedding the surfaces of the cutter disk which project beyond the end of said head and providing a cushion between the flexible arcuate portion of the hood and the cutter disk.
